A. W. Riley,
Chas. S. Brock

UNITED STATES PATENT OFFICE.

FRANCIS LEROY HORSPOOL, OF OGDEN, UTAH, ASSIGNOR OF ONE-HALF TO
GEO. J. KELLY, OF SAME PLACE.

DOOR FOR STEAM-BOILER FURNACES.

SPECIFICATION forming part of Letters Patent No. 605,576, dated June 14, 1898.

Application filed September 23, 1897. Serial No. 652,717. (No model.)

To all whom it may concern:

Be it known that I, FRANCIS LEROY HORSPOOL, residing at Ogden, in the county of Weber and State of Utah, have invented a new and useful Door for Steam-Boiler Furnaces, of which the following is a specification.

This invention relates generally to doors for steam-boiler furnaces, and more particularly to one used in connection with a draft-opening above the fire, and also to a deflector-plate.

The object of this invention is to provide a furnace-door which will save time and labor in firing a furnace and will also admit the required amount of air above the fire in the fire-box to supply oxygen to complete the combustion of the carbon of the fuel and to economize in the consumption of fuel, the door being made in sections capable of independent operation, whereby it may be kept partially or wholly open.

Another object of my invention is to provide a furnace-door with a draft-regulator opening above the fire.

Another object of my invention is to provide a furnace-door which can be left open all the time during firing.

Another object of my invention is to provide a furnace-door which when open will lie flat out of the way of the fireman.

Another object of my invention is to provide an improved locking means for securing the door.

Another object of my invention is to provide means for admitting oxygen or air into the fire-box above the fire.

Another object of my invention is to provide means for regulating the amount of air admitted into the fire-box above the fire through the door-opening.

A still further object of my invention is to construct a door which can be left partially open while the engine is working steam, so that it will let in oxygen enough to complete the combustion of the carbon of the coal and do away with the black smoke.

A still further object of my invention is to admit the required amount of air to the fire for the gases above the fire.

With these and other objects in view my

invention consists in the improved construction, arrangement, and combinations of parts hereinafter fully described and afterward specifically pointed out in the claims.

In order to enable others skilled in the art to which my invention most nearly appertains to make and use the same, I will now proceed to describe its construction and operation, reference being had to the accompanying drawings, forming part of this specification, in which—

Figure 1 is a view in rear elevation of the cab and boiler-head of a locomotive, showing my invention in place, the door being wholly closed. Fig. 2 is a similar view showing the door and frame, with the door partially open, as in use, while the engine is working steam. Fig. 3 is a similar view showing the door entirely open. Fig. 4 is a vertical sectional view through the door, its frame, and the deflector, showing the relative positions of the door and deflector-plate. Fig. 5 is a fragmentary detail view showing the adjusting and holding mechanism for the deflector-plate.

Like letters of reference mark the same parts wherever they occur in the different figures of the drawings.

Referring to the drawings by letters, A is the boiler-head of a locomotive, in the opening of which is secured a door-frame B, having an outwardly-projecting flange C, over which the door fits when closed. The door is hinged to the frame B at the bottom by means of hinges D and is composed of two sections E and F, these sections being secured together by hinges G, so that the whole door may be closed, the upper section alone opened, or both sections opened.

H and H' are bell-crank levers pivoted at their angles to the upper outer corners of the door-frame B, their horizontal arms lying along the upper face of the door-frame and being provided with a bifurcated end H² and a rounded end H³, whereby when one is oscillated upon its pivot the other will partake of its motion. The vertical arms of the bell-crank levers H and H' extend along the sides of the door-frame and are provided with horizontal inwardly-bent points H⁴ and H⁵, which pass through lugs H⁶ and H⁷, and en-

gaging the outside of the lower section E of the door serve to hold it closed. A latch I upon the upper section of the door engages a latch I' on the door-frame and serves to hold 5 the upper section closed. The bell-crank lever II is provided with a handle II³, by which it and its fellow lever II' may be manipulated. The lower section E of the door is provided with a series of draft-openings J, which 10 may be regulated in extent or wholly closed by a plate K, slidably secured on the inner side of the door. This plate is vertically slotted at L L', and bolts M, passing through said slots, entering the door-section, serve to hold 15 the plate slidably against the inner side of the door-section. On the outer side of the door-section is pivoted a lever N, having its inner end slotted horizontally, a bolt O passing through its slot, and a vertical slot P in 20 the door-section enters the draft-plate K, whereby the oscillation of the lever on its pivot vertically will carry the draft-plate with it to partially or wholly close the draft-openings J.

25 Pivoted to one of the flanges G of the door frame B is a baffle-plate or deflector R, which is as wide as the door and a little longer and normally rests in an inclined elevated position, the edges being bent downward and 30 the side edges inclined slightly toward the center, whereby air entering through the door is deflected and prevented from coming in direct contact with the crown-sheet of the fire-box or flues of the boiler. The pivot Q 35 of the deflector-plate is extended through the flange C of the door-frame and is provided with a rigid crank-like arm S, which has a threaded opening through which passes a bolt T, having on its outer end a hand-wheel U, 40 whereby by turning the bolt inward or outward through the crank-arm S, with its inner end bearing against the door-plate, the deflector-plate is adjusted in position higher or lower, as may be desired. This deflector-plate 45 serves also to conduct the cold-air draft to the center of the fire-box, thereby supplying oxygen at the proper point to complete the combustion of the carbon of the fuel.

The provision of a door made in upper and 50 lower sections permits the furnace to be fired without the necessity of opening and closing the whole door, and inasmuch as the door is partially open all the time during the firing and is partially open all the time while the 55 engine is working steam a sufficient amount

of oxygen is admitted to the fire to complete the combustion of the smoke and coal-gas, whereby the objectionable black smoke is dispensed with and much waste avoided.

By having the door open horizontally instead of vertically, as is the case with doors in general use on our railroads at the present time, it may be made of sufficient width and it will be entirely out of the way of the fireman, thereby facilitating his work. 60 65

While I have illustrated and described the best means now known to me for carrying out my invention, I do not wish to be understood as restricting myself to the exact details of construction shown and described, but hold that 70 any slight changes or variations, such as might suggest themselves to the ordinary mechanic, will properly fall within the limit and scope of my invention.

Having thus fully described my invention, 75 what I claim as new, and desire to secure by Letters Patent of the United States, is—

1. The combination in a steam-boiler furnace with the door-frame, of a door comprising an upper and a lower section, the lower 80 section being hinged at its lower edge to the door-frame, and the upper section being hinged at its lower edge to the upper edge of the lower section, and bell-crank levers pivoted near the upper corners of the door-frame 85 having their horizontal arms which pass along the upper edge of the door-frame arranged to move synchronously and provided at the lower end of their vertical arms with horizontal points adapted to project outside of 90 and lock the lower section of the door, substantially as described.

2. The combination of a steam-boiler furnace with the door-frame, of a door comprising an upper and a lower section, the lower 95 section being hinged at its lower edge to the door-frame, and the upper section being hinged at its lower edge to the upper edge of the lower section, the lower section being provided with draft-openings, a slideable plate on 100 the inside of said door-section for regulating said draft-openings, and a lever pivoted on the outside of the door and connected through the slot in the door with said slideable plate whereby the same is operated, substantially 105 as described.

FRANCIS LEROY HORSPOOL.
